His ATTORNEY

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC LAMP.

Continuation of application Serial No. 364,485, filed March 9, 1920. This application filed August 24, 1921. Serial No. 494,823.

To all whom it may concern:

Be it known that I, SAMUEL M. LUCAS, a citizen of the United States, residing at Pittsburgh, in the county of Allegheny and 5 State of Pennsylvania, have invented certain new and useful Improvements in Electric Lamps, of which the following is a specification.

My invention relates to electric lamps, 10 and has for an object the provision of means for indicating at a distant point whether or not a lamp is lighted.

Broadly stated, I accomplish this object by using for a lamp a rectifying device having a filament and an anode, the filament serving as the luminous element of the lamp. The indication means is controlled by a circuit which includes the filament and anode as well as a source of alternating current. 15 20 Inasmuch as current can flow in such circuit only when the filament is hot, it follows that the indication means will respond only when the filament is actually lighted.

Apparatus embodying my invention is 25 capable of general application, but is particularly well adapted for accomplishing the desired "return indication" when light signals are used in interlocking systems for railways, that is, systems wherein a group of 30 switches and signals are controlled from a central point by an interlocking machine.

In connection with interlocking apparatus, it is well understood that means must be provided for locking each signal lever in 35 a preliminary or indicating position while moving from proceed towards stop position, and for releasing the lever only when the signal controlled thereby has assumed the stop aspect in response to the preliminary 40 movement of the lever. The releasing means is usually termed the indication device.

When signals of the light type are employed in interlocking apparatus, each signal usually comprises at least two electric 45 lamps of the incandescent filament type, which indicate "stop" and "proceed", respectively, when illuminated, the circuits for the lamps being controlled by contacts actuated by the signal lever. It follows, then, that means 50 should be provided for operating the indication device on the lever only when the "stop" lamp is illuminated.

When my invention is applied to appara-

tus of this character, I provide means for releasing the lever from indicating position 55 only when the filament of the stop lamp is actually hot enough to give the stop indication.

The present application is a continuation of my co-pending application, filed on the 60 9th day of March, 1920, Serial No. 364485, for railway traffic controlling apparatus, in so far as the subject matter common to the two is concerned.

I will describe several forms of apparatus 65 embodying my invention, and will then point out the novel features thereof in claims.

In the accompanying drawings, Fig. 1 is a diagrammatic view showing one form of 70 apparatus embodying my invention. Fig. 2 is a fragmental view showing a modification of part of the indication device shown in Fig. 1. Fig. 3 is a view showing another form of indication device which may be 75 substituted for the device shown in Fig. 1. Fig. 4 is a view similar to Fig. 1 but showing a modification of the apparatus illustrated therein. Fig. 5 is a view showing an alternative form of indication device which 80 may be substituted for the device shown in Fig. 4. Fig. 6 is a view showing still another modification of the apparatus shown in Fig. 1. Fig. 7 is a view showing a position light signal having applied thereto one 85 form of apparatus embodying my invention.

Similar reference characters refer to similar parts in each of the several views.

Referring first to Fig. 1, the reference character S designates a railway signal comprising two electric lamps G and R. Lamp G is an ordinary incandescent filament lamp, whereas lamp R is in the form of a rectifier comprising a filament 3 and an anode 4, both of which are enclosed in a bulb from 90 which the air has been exhausted. The filament 3 constitutes the luminous or lighting element of the lamp R. Located in front of the lamps G and R, respectively, are two lenses 2^G and 2^R, which are preferably 95 colored green and red, respectively, and each of which serves to project a beam of light from the corresponding lamp when the lamp is illuminated. In accordance with 100 usual practice, the signal indicates "proceed" 105 when lamp G is illuminated, and "stop" when lamp R is illuminated.

when lamp R is illuminated, the indication, of course, being determined by the color of the light beam projected by the signal.

- The lamps in signal S are controlled by a lever L, which is usually one of a plurality of similar levers in an interlocking machine. As here shown, this lever is mounted to slide longitudinally, and it is provided with a grip 5 to facilitate manipulation by hand.
- 5 In accordance with usual interlocking practice, the lever L has three controlling positions, known as "reverse", "indicating" and "normal" positions, respectively. The control of the signal is such that the proceed lamp G is illuminated when the lever is in the "reverse" position, and that the stop lamp R is illuminated when the lever is in the "indicating" and "normal" positions. As shown in the drawing, the lever is in the 15 reverse position, the circuit for the proceed lamp G being from the secondary of a transformer T^a, through wire 15, contact 6—8 on lever L, wire 16, lamp G, wire 17, and common wire O to the secondary of transformer T^a. The primary of transformer T^a is supplied with operating or lighting alternating current from a source which is not shown.
- When lever L is moved to the left from the position shown in the drawing, it is arrested 30 in the indicating position by the engagement of a latch 11 with a shoulder 21 on the lever. This movement of the lever opens contact 6—8 and closes a contact 6—9, so that the proceed lamp G, becomes extinguished and current is supplied to an auto transformer U, the circuit being from the secondary of transformer T^a, through wire 15, contact 6—9, wires 18 and 18^a, winding of auto transformer U, and common wire 35 O to the secondary of transformer T^a. Filament 3 of stop lamp R is connected across a portion of the winding of the auto transformer, so that this lamp is then lighted.
- 40 While the lever is in the indicating position, an indication circuit is closed, which circuit passes from the secondary of transformer T^a through wire 15, contact 6—9, wire 18, wire 19, contact 10—7, wire 20, primary of an indication transformer T^b, indication wire I, anode 4 and filament 3 of lamp R, and common wire O to the secondary of transformer T^a. If filament 3 is hot enough to radiate the proper amount of 45 light for signal purposes, current will flow in this circuit in one direction, that is, from anode to filament, but not in the other direction, so that the primary of transformer T^b is supplied with a rectified or pulsating 50 direct current which varies from zero to maximum and back to zero in the time required for one-half of a complete cycle of the operating current from transformer T^a. It follows that this pulsating current will 55 induce in the secondary of transformer T^b

an alternating current having a large component the frequency of which is twice that of the current delivered by transformer T^a. A composite current having the fundamental component and a component of twice the 70 fundamental frequency is delivered to the stator winding 14 of an induction motor M the rotor 13 of which operates a centrifugal device C. This centrifugal device C in turn actuates the latch 11 in such manner as to lift this latch out of the path of shoulder 21 when the centrifugal device operates at a predetermined speed. Inasmuch as motor M is of the induction type, its speed will be between the speed corresponding to the fundamental frequency and that corresponding to the higher frequency. The centrifugal device C is so adjusted that when it is driven at this speed it will elevate the latch 11, but that if motor M 80 should be operated by current of the frequency supplied by transformer T^a, the latch 11 will not be elevated.

After the indication has been received, that is, after latch 11 is elevated, the lever 90 L may be moved still farther to the left to its "normal" position wherein contact 7—10 is opened so that motor M is de-energized. Contact 6—9 remains closed, however, so that stop lamp R continues to be illuminated.

It will be seen from the foregoing that the indication device for lever L cannot be falsely operated by stray direct current, or by alternating current of less than a predetermined frequency which frequency is higher than that of the operating current supplied to the lamps by transformer T^a.

If the wave shape of the current in the secondary of transformer T^b be analyzed, it will be found to comprise the fundamental wave (the wave shape of the current from transformer T^a) predominating, and a second harmonic of nearly equal magnitude. If desired, the scheme shown in Fig. 2 may be employed, wherein a selective device X comprising reactances 22, 22^a and condensers 23, 23^a, is interposed between transformer T^b and motor M to tune out the fundamental wave and leave only the second harmonic to operate the motor. As with the apparatus shown in Fig. 1, motor M must be operated at a speed corresponding to twice the frequency of the signal operating current in order to release the lever L. The advantage of the structure shown in Fig. 2 is that due to the elimination of the fundamental wave, the motor will operate at higher speed than is the case with the arrangement shown in Fig. 1.

Referring now to Fig. 3, I have here shown a modification of the device controlled by the indication current for releasing the lever L. In this modification the latch 11 is elevated by the armature 51 of

a polarized magnet P, which in turn is energized directly from the indication circuit. This magnet P is so arranged that it will elevate the latch only when energized 5 by direct or pulsating current which flows from anode 4 to the filament 3 in lamp R. It follows that this indication device will not respond to stray alternating current, or to alternating current from transformer T^a.

Referring now to Fig. 4, the lamps G and R are controlled by lever L in the same manner as in Fig. 1, except that the primary of the indication transformer T^b is included in the signal control wire leading from lever 15 contact 9 to the auto transformer U. The anode 4 is connected to wire 18^b through a resistance 24, so that when contact 6-9 is closed and filament 3 is hot, a pulsating current flows through the primary of transformer T^b and resistance 24 to the anode, which current, in transformer T^b is superposed on the operating current supplied to the filament. The result in the secondary of transformer T^b is an electromotive force 20 which, when analyzed, will be found to comprise the fundamental wave and a second harmonic of considerable magnitude. The fundamental wave is tuned out by a selective device X, which is similar to the device 25 shown in Fig. 2, so that motor M is supplied with an alternating current of twice the frequency of the operating current. Latch 11 is controlled by motor M in the same manner as in Fig. 1.

The structure shown in Fig. 4 is so arranged that motor M and centrifuge C operate continuously to elevate the latch 11 when the stop lamp R is illuminated. If desired, therefore, the centrifugal device 40 may be used to give a positive and continuous indication at the interlocking machine that the signal indicates "stop." As here shown, this is accomplished by a red lamp R^a and a green lamp G^a located adjacent the lever L, which lamps are controlled by a contact finger 25 operatively connected with the latch 11. When the signal indicates "proceed," that is, when red lamp R is extinguished, the latch 11 is depressed, so that contact finger 25 engages with a fixed contact 26 and thereby completes a circuit including the green lamp G, which circuit will be obvious from the drawing. On the other hand, when the stop 45 lamp R is illuminated, latch 11 is elevated so that contact finger 25 engages with a fixed contact 27 to complete a circuit through the red lamp R^a. This arrangement gives a continuous indication at the machine that the signal is at "stop," and it instantly indicates the occurrence of a failure of the stop lamp R due to any cause whatsoever.

Referring now to Fig. 5, I have here shown a modified form of indication apparatus which may be substituted, if desired,

for the apparatus shown in Fig. 4. If the current in the primary of transformer T^b in Fig. 4 be analyzed, it will be found to comprise a direct current component and an alternating current component. The apparatus shown in Fig. 5 is designed to require the presence of both of these components in order to release the lever from the indicating position. This apparatus comprises two latches 11 and 11^a, which coact with shoulders 21 and 21^a, respectively, on the lever L. These latches are controlled by two armatures 28 and 28^a, respectively, which armatures are in turn controlled by an electromagnetic device A. The device A comprises two magnetizable cores 29 and 30 connected by two magnetizable bridges 32 and 33, the cross-sectional area of the latter being comparatively small. The cores 29 and 30 are provided with a winding 31 which is included in the signal control wire 18^a-18^b in the same manner as the primary of transformer T^b in Fig. 4. The cores 29 and 30 are provided with copper bands 35 and 36 respectively, and a similar band 34 surrounds the bridge 32.

Each armature 28 and 28^a is biased to the open position wherein the latch controlled thereby is depressed, hence it follows that lever L can be released only when both armatures are closed. Assuming now that the "stop" lamp R is illuminated, the greater part of the alternating component of the magnetic flux due to the current in winding 31 will be forced away from armature 28^a due to bands 35 and 36, and will be forced through armature 28 due to the band 34 on bridge 32, so that this flux will cause armature 28 to close but will not affect armature 28^a. The direct component of the flux will, however, be shunted away from armature 28 by bridge 32 and will be forced through armature 28^a owing to the high reluctance of bridge 33, so that this flux will close armature 28^a but will not affect armature 28. It will be seen, therefore, that both armatures are closed only when the current flowing in winding 31 comprises a direct component and an alternating component, that is, only when the signal operating current in this winding is modified by the rectified current taken by the resistance 24 and the anode 4 of the stop lamp.

As shown in Fig. 5, the armatures 28 and 28^a are employed to control two auxiliary lamps G^a and R^a, the functions of which are the same as those of the corresponding lamps in Fig. 4. For this purpose armature 28 is provided with a contact finger 25 and armature 28^a is provided with a similar contact finger 25^a. When both armatures are open, that is, when the signal indicates proceed, the green lamp G^a is illuminated, owing to the fact that contacts 26^a are bridged by contact finger 25^a, and contacts 26 are bridged

by contact finger 25. When both armatures are closed, however, that is, when the signal indicates stop, the red lamp R^a is illuminated, owing to the fact that contacts 27 are bridged by contact finger 25 and contacts 27^a are bridged by contact finger 25^a. It will be seen, therefore, that if the stop lamp R is extinguished for any reason whatsoever, one or both of the armatures 28, 28^a will open, so that the auxiliary lamp R^a will be extinguished.

Referring now to Fig. 6, I have here shown means for utilizing both halves of the wave of the operating current for indication purposes. The red or stop lamp, which is here designated R^b contains two anodes 4^a and 4^b. The filament 3 in this lamp is in this instance supplied with current by the secondary of a transformer B, the primary of which is controlled by contact 6—9 on lever L in the same manner as the auto transformer U in Fig. 1. The proceed lamp G is likewise controlled in the same manner as in Fig. 1.

The two anodes 4^a and 4^b are connected with the terminals of the primary of transformer B by wires 38 and 39, so that the potentials of these anodes alternate with the potentials of the terminals of the secondary of transformer T^a . The indication wire I is in this case connected with the filament 3, whereas wire 20^a, which leads from the primary of transformer T^b , passes to contact 10. Lever contact 7 is connected by a wire 40 with the middle point of a reactance 37 the terminals of which are connected across the secondary of transformer T^a .

I will now assume that the lever L is moved to the left to the indicating position, and that the filament 3 becomes hot enough to display the proper signal. During one half of a cycle of the current supplied by transformer T^a the anode 4^a will be positive, whereupon current will flow from the secondary of transformer T^a , through common wire O, wire 38, anode 4^a, filament 3, indication wire I, primary of transformer T^b , wire 20^a, contact 10—7, wire 40, and the right-hand half of reactance 37 to the right-hand terminal of the secondary of transformer T^a . During the succeeding half cycle anode 4^b will be positive, so that current will then flow from the right-hand terminal of the secondary of transformer T^a , through wire 15, contact 6—9, wire 18, wire 39, anode 4^b, filament 3, indication wire I, primary of transformer T^b , wire 20^a, contact 10—7, wire 40, and the left-hand half of reactance 37 to the secondary of transformer T^a . During this latter half cycle anode 4^a is negative with respect to the filament, so that no current flows in the circuit first traced. Similarly, during the first half cycle anode 4^b is negative with respect to the filament, so that no current flows in the second circuit. The

result of this alternate action of the two branches of the indication circuit is to produce pulsating current in the primary of transformer T^b which varies from zero to maximum and back to zero in the time required for the operating current to pass through one-half of a cycle. It follows that the frequency of the electromotive force induced in the secondary of transformer T^b is twice the frequency of the operating current delivered by transformer T^a . The fundamental wave is entirely absent, so that a frequency selective device, such as that shown in Fig. 2 is not required. The control of the latch 11 is exactly the same as in Fig. 1.

Referring now to Fig. 7, I have here shown my invention as applied to what is known as a "position light signal." The signal, which is here designated S^a , comprises a plurality of electric incandescent lamps G, arranged in a vertical row, and a plurality of other lamps R, arranged in a horizontal row, a special lamp R' , which is known as the pivot lamp, being common to the two rows. When the lamps in the vertical row are illuminated, the signal indicates proceed, and when the lamps in the horizontal row are illuminated, the signal indicates stop. As here shown, the lamps in the horizontal row and the pivot lamp R' are each in the form of a rectifier having an anode 4, whereas the lamps in the vertical row, with the exception of the pivot lamp, are ordinary incandescent lamps.

The filament of the pivot lamp R' is constantly illuminated by virtue of current supplied thereto from the secondary of a transformer T^c . The primary of this transformer is constantly supplied with current from transformer T^a , the circuit being through wires 15^a and 41, primary of transformer T^c , wire 42 and common wire O. When the lever L is in its reverse position, wherein it is shown in the drawing, the proceed lamps are illuminated, the circuit being from the secondary of transformer T^a , through wires 15^a and 15, contact 6—8, wire 16, thence through the filaments of the three lamps G in multiple to wire 17, and from this wire through common wire O to the secondary of transformer T^a .

The filament of each stop lamp R is supplied with current by a separate secondary winding in a transformer T^d . The circuit for the primary of transformer T^d is from the secondary of transformer T^a , through wires 15^a and 15, contact 6—9, wires 18 and 18^a, primary of transformer T^d , wire 50 and common wire O to the secondary of transformer T^a .

It will be seen from the foregoing that the proceed lamps are illuminated when

the lever is in its reverse position and that the stop lamps are illuminated when the lever is in indicating and normal positions.

5 The indication circuit for the primary of transformer T^b passes from the left-hand terminal of the secondary of transformer T^a , through common wire O , wire 43, anode 4, and filament 3 of the left-hand lamp R , wires 44 and 45, anode and filament of pivot lamp R' , wires 46 and 47, anode and filament of the middle stop lamp R , wires 48 and 49, anode and filament of the right-hand lamp R , indication wire I , primary of transformer T^b , wire 20, contact 7—10, wire 18, contact 9—6, and wires 15 and 15^a to the secondary of transformer T^a . It will be noted that this indication circuit includes in series the anode and filament of each lamp in the horizontal row, so that current will be supplied to transformer T^b only when the filament of each of these lamps is actually hot enough to give the proper visual signal. During the half cycle 25 when the common wire O is positive with respect to wire 18^a, a current will flow through the indication circuit, which current will have the same characteristics as the indication current in the structure shown 30 in Fig. 1. The fundamental wave in the electromotive force induced in the secondary of transformer T^b may be tuned out by a selective device X , so that the current supplied to motor M is of twice the frequency 35 of the operating current. The control of latch 11 by motor M is the same as in Fig. 1.

Although I have herein shown and described only certain forms of apparatus embodying my invention, it is understood that 40 various changes and modifications may be made therein within the scope of the appended claims without departing from the spirit and scope of my invention.

Having thus described my invention, what 45 I claim is:

1. In combination, an electric lamp in the form of a rectifier having a filament and an anode, means for supplying lighting current to said filament, a device for indicating at a distance whether or not said lamp 50 is lighted, and a circuit for controlling said device and including the filament and anode of said lamp and a source of alternating current.

2. In combination, an electric lamp in the form of a rectifier having a filament and an anode, an auto transformer, said filament being connected across a portion of the winding of said transformer, means for 60 supplying alternating current to said transformer, an indication device, and means connected with said anode and said transformer for controlling said device.

3. In combination, an electric lamp in 65 the form of a rectifier having a filament

and an anode, means for supplying alternating lighting current to said filament, indication means responsive to current of higher frequency than that of said lighting current but not to current of the frequency of said lighting current, and a circuit for controlling said indication means supplied with current from said lighting source and including said filament and anode. 70

4. In combination, an electric lamp in the form of a rectifier having a filament and an anode, means for supplying alternating lighting current to said filament, an indication circuit supplied with current from said lighting source and including said filament and anode and the primary of a transformer, and indication means supplied with current from the secondary of said transformer and responsive to current of higher frequency than that of said lighting current but not to current of the frequency of the lighting current. 80

5. In combination, an electric lamp in the form of a rectifier having a filament and an anode, means for supplying alternating lighting current to said filament, an indication circuit supplied with current from said lighting source and including said filament and anode and the primary of a transformer, 90 indication means supplied with current from the secondary of said transformer and responsive to current of higher frequency than that of said lighting current but not to current of the frequency of the lighting current, and means interposed between said transformer secondary and said indication means for tuning out current of said lighting frequency. 95

6. In combination, a railway signal comprising a lamp in the form of a rectifier having a filament and an anode, a source of alternating current, a lever, means controlled by said lever for supplying operating current to said filament from said source, and indication circuit supplied with current from said source and including the filament and anode of said lamp, and locking means for said lever controlled by current in said indication circuit. 100

7. In combination, a railway signal comprising a lamp in the form of a rectifier having a filament and an anode, a source of alternating current, a lever, means controlled by said lever for supplying operating current to said filament from said source, an indication circuit supplied with current from said source and including the filament and anode of said lamp, means for locking said lever, and apparatus controlled by the current in said indication circuit and responsive to such current but not to the operating current supplied to said filament for releasing said locking means. 115

8. In combination, a railway signal com- 120

prising a lamp in the form of a rectifier having a filament and an anode, a source of alternating current, a lever having "proceed", "indicating" and "stop" positions, means controlled by said lever for supplying operating current to said filament from said source when the lever is in indicating and stop positions but not when it is in proceed position, an indication circuit supplied with current from said source and including said filament and anode, means for locking said lever in the indicating position while moving from the proceed towards the stop positions, and means controlled by the current in said indication circuit for releasing said locking means.

9. In combination, a railway signal comprising a lamp in the form of a rectifier having a filament and an anode, a lever, means controlled by said lever for supplying operating current to said filament, an indication circuit including said filament and said anode and a source of alternating current, and locking means for said lever controlled by the current flowing in said indication circuit.

10. In combination, a light signal comprising a rectifier having a filament and an anode, an auto transformer, said filament being connected across part of the winding of said transformer, a source of alternating current, a lever for controlling the supply of current from said source to said transformer, a locking device for said lever, and electromagnetic means connected to said anode and to the winding of said auto transformer for releasing said lever locking device.

11. In combination, a railway signal comprising a rectifier having a filament and an anode, a source of alternating current, a lever, means controlled by said lever for supplying operating current to said filament from said source, an indication circuit supplied with current from said source and including the filament and anode of said signal and the primary of a transformer, a device for locking said lever, and electrical means receiving energy from the secondary of said transformer for releasing said lever locking device when energized by alternating current of twice the frequency of said source but not when energized by current of the frequency of said source.

12. In combination, a railway signal comprising a rectifier having a filament and an anode, a source of alternating current, a lever, means controlled by said lever for supplying operating current to said filament from said source, an indication circuit supplied with current from said source and including the filament and anode of said signal and the primary of a transformer, a device for locking said lever, a motor receiving energy from the secondary

of said transformer, and a centrifugal device operated by said motor for releasing said lever locking device when the motor receives alternating current of twice the frequency of said source but not when the motor receives current of the frequency of said source.

13. In combination, a railway signal comprising a rectifier having a filament and an anode, a lever, means controlled by said lever for supplying operating current to said filament, an indication circuit including said filament and said anode and a source of alternating current, a locking device for said lever, and electro-responsive means controlled by said indication circuit for releasing said locking device.

14. In combination, a railway signal comprising a rectifier having a filament and an anode, a source of alternating current, a lever, means controlled by said lever for supplying operating current to said filament from said source, an indication circuit supplied with current from said source and including said filament and anode and the primary of a transformer, a locking device for said lever, electrical means receiving energy from the secondary of said transformer and responsive to current of twice the frequency of said alternating current source but not to current of the frequency of said source for releasing said locking device, and means interposed between said transformer secondary and said electrical means for tuning out current of the frequency of said source.

15. In combination, a light signal in the form of a rectifier having a filament and an anode, an auto transformer, said filament being connected across part of the winding of said transformer, a source of alternating current, an operating circuit including said source and said auto transformer and also the primary of a second transformer, a resistance connected across said anode and a terminal of said auto transformer, a lever for controlling said operating circuit, a locking device for said lever, electrical means receiving energy from the secondary of said second transformer and responsive to current of twice the frequency of said source but not to current of the frequency of said source for releasing said locking device, and means interposed between said transformer secondary and said electrical means for tuning out current of the frequency of said source.

16. In combination, a light signal in the form of a rectifier having a filament and an anode, an auto transformer, said filament being connected across part of the winding of said transformer, a source of alternating current, an operating circuit including said auto transformer and said source and the primary of a second transformer, a lever for controlling said operating circuit, a re-

sistance connected across said anode and a third point in said auto transformer, a locking device for said lever, electrical means receiving energy from the secondary of said 5 second transformer and responsive to current of twice the frequency of said source but not to current of the frequency of said source for releasing said locking device, and means interposed between the 10 secondary of said second transformer and said electrical means for tuning out current of the frequency of said source.

17. In combination, an incandescent electric lamp comprising a filament and an anode, a circuit including said filament and 15 said anode as well as a source of alternating

current and the primary of a transformer, a motor receiving energy from the secondary of said transformer, a centrifugal device operated by said motor, and indication means 20 for said lamp controlled by said centrifugal device.

18. In combination, an incandescent electric lamp comprising a filament and an anode, an anode circuit for said lamp, a motor 25 receiving energy from said anode circuit, a centrifugal device operated by said motor, and indication means for said lamp controlled by said centrifugal device.

In testimony whereof I affix my signature.

SAMUEL M. LUCAS.
